UNITED STATES PATENT OFFICE.

EDWARD A. HOOVER, OF BRADLEY, AND WILLIAM C. KIRCHNER, OF KANKAKEE, ILLINOIS.

MITER BOX.

Application filed June 3, 1925. Serial No. 34,517.

Our invention relates generally to miter boxes and more particularly to compound miter boxes in which the saw guiding frame may be adjusted about a horizontal axis as 5 well as about a vertical axis.

The general object of our invention is to provide an improved miter box in which the saw frame may be readily adjusted about a vertical axis and about a horizontal axis to 10 various angles and inclinations and effectively secured in the adjusted position.

A further object of our invention is to provide an improved miter box in which the saw will be guided so as to always cut the 15 intersection of the table and back at the same point irrespective of the angular adjustment of the saw frame, thereby permitting accurate measurement of the material being cut.

20 Further objects and advantages will be understood from the following detailed description taken in connection with the accompanying drawings in which

Figure 1 is a plan view of the preferred 25 form of our invention herein described.

Fig. 2 is a front elevation thereof.

Fig. 3 is a section taken on the lines 3—3 of Fig. 2, looking in the direction of the 30 arrows.

Fig. 4 is a fragmental rear elevation showing the indexing and clamping means for the saw frame.

Fig. 5 is a section taken on the lines 5—5 of Fig. 1, looking in the direction of the 35 arrows.

For purposes of disclosure, we have illustrated in the drawings and will hereinafter describe in detail the preferred embodiment of our invention, with the understanding 40 that we do not intend to limit our invention to the particular construction and arrangement shown, it being contemplated that various changes may be made by those skilled in the art without departing from the spirit 45 and scope of the appended claims.

Referring to the accompanying drawings, 50 our invention in the exemplary form comprises a cast metal base 1, having raised end portions 2 forming a divided horizontal work table adapted to support the work, such as a board or studding to be cut. A suitable back is provided to guide the board along the work table 2, this back being herein shown as consisting of plates 4, secured to 55 the base by means of cap screws 5 in a posi-

tion perpendicular to the work table 2, although the back might readily be cast integral with the base. The portion 3 of the base intermediate of said end portions is of the shape of a sector as shown in Fig. 1, 60 this sector portion being provided with a vertical pivot bolt 6 with its axis in the plane of the backs 4. A scale 7 adjacent the front curved edge of the sector 3 reads in degrees both ways from the center line 8 of the 65 sector to indicate angular displacement therefrom.

A saw frame bearing member or block 9, mounted on the sector portion 3 of the base in engagement with the pivot bolt 6 is rotatable thereabout through an angle of 90°. The portion 10 of this block 9 which crosses the work table 2 is preferably finished off in the horizontal plane of the table to serve as an additional support for the work, this additional support being thereby provided immediately adjacent the cutting edge of the saw. This block is also provided with a longitudinal groove 11 semi-circular in cross-section which serves as a bearing trough 80 throughout the length of the block.

Means is provided to indicate the angle at which the block 9 is disposed from the center line 8 and to secure the block in such position, this means being herein shown as 85 comprising an L-shaped bracket 12 attached to the forward end of the block by cap screws, said bracket depending over the front edge of the sector portion 3 of the base 1. This depending portion 13 is provided 90 with a hole 14 therethrough which is positioned so that it may register with any one of several tapped holes 15 in the forward edge of the sector portion 3 of the base; these tapped holes being located immediately 95 below the division marks of the scale 7. A thumb screw 16, adapted to pass through the hole 14 in the bracket 12 and engage any of the tapped holes, is provided to effectively secure the block 9 in its adjusted position.

A U-shaped saw frame 17 is pivotally mounted in the bearing block 9, the uprights 18 and cross bar 19 of this frame being bifurcated at 20 to admit a back saw (not shown) and thereby guide it. The cross bar 19 has a cylindrical surface 21 to coat with the bearing trough 11 of the bearing block 9. At each end of the cross bar 19 and beyond the edges of the work table 2 110

the cross bar is of circular section for a substantial distance as at 22 and 23. Adjacent these cylindrical portions, the sides of the bearing block 9 extend upward above the 5 plane of the work table as shown in Figs. 2, 4 and 5 to form bearings 24 and 25 for the cross bar and thereby effectively retain the saw frame 17 in the bearing block. The portion of the cross bar between the bearings 10 thus formed is reduced in section as shown at 26 in Fig. 5, in order that it shall not project above the plane of the work table 2 when the saw frame is tilted. Thus, the saw frame 17 is pivoted for adjustment 15 about a horizontal axis in the plane of the work table 2.

To secure the frame 17 in any of its pivoted positions and to indicate the angle at which it is inclined, we provide a plate 27 20 secured to the bearing block 9 in a vertical position by any suitable means. This plate has an arcuate slot 28 therethrough and a scale 29 along the lower edge of the slot. A suitable index may be provided fixed to the 25 saw frame to indicate on this scale the angle of inclination of the frame, such an index being herein shown as comprising a depending arm 30 having a pointer 31, said arm being secured to the saw frame by means 30 of screws 30^a. This arm 30, in addition to its use as an index, comprises means to secure the saw frame in its adjusted position and against longitudinal movement. For this added purpose the arm has a hole 32 35 therethrough coinciding with the arcuate slot 28 to admit a suitable thumb screw 33 adapted to engage a nut 34 and thereby clamp the saw frame rigidly.

From the foregoing it will be apparent 40 that we have provided an improved miter box in which the saw frame is readily adjustable about a horizontal as well as a vertical axis, and in which, irrespective of the angular adjustment and inclination of the 45 frame, the saw will be guided to cut the intersection of the work table and back at the center line of the table, thereby permitting accurate measurement of the material being cut.

50 We claim as our invention:

1. A miter box having, in combination, a base comprising raised end portions and an intermediate sector portion, said end portions forming a divided work table, a divided 55 back, a member pivotally mounted on said sector portion for adjustment about a vertical axis in the plane of said back, means to secure said member in its adjusted position, said member having bearings at each end thereof and a bearing trough semicircular in section throughout its length, a U-shaped saw frame pivoted in said member and adjustable about a horizontal axis in the plane of said work table, said saw frame comprising

ing a cylindrically surfaced cross bar coact- 65 ing with said bearings and trough, and a pair of bifurcated arms extending perpendicular thereto adapted to guide a saw across said table, said cross bar having its central portion between said bearings reduced in 70 section so as not to extend above the plane of the said table, said member having a plate member depending from one end thereof, said saw frame having a guide member depending therefrom adjacent said plate member, and means to clamp said plate member and guide member in fixed relation to secure said saw frame in its adjusted position and against longitudinal movement.

2. A miter box having, in combination, a base comprising raised end portions and an intermediate sector portion, said end portions forming a divided work table, a divided back, a member pivotally mounted on said sector portion for adjustment about a vertical axis in the plane of said back, means to secure said member in its adjusted position, said member having bearings at each end thereof, a U-shaped saw frame pivoted in 85 said bearings for adjustment about a horizontal axis in the plane of said table, said saw frame comprising a cross bar having cylindrical end portions coacting with said bearings and a pair of bifurcated arms extending perpendicular thereto adapted to 90 guide a saw across said table, the portion of said cross bar intermediate said bearings being reduced in section so as not to extend above the plane of the table, and means to 95 secure said saw frame in its adjusted position and against longitudinal movement comprising a plate member depending from said member, a guide member secured to said saw frame and adjacent said plate member and means to secure said plate member and said 100 guide member in fixed relation.

3. A miter box having, in combination, a base comprising a divided work table and an intermediate sector portion in a lower plane than said table, a divided back, a member pivotally mounted on said sector portion for adjustment about a vertical axis in the plane of said back, means to secure said member in its adjusted position, said member having 110 bearings at each end thereof and a bearing trough therebetween, a U-shaped saw frame pivoted in said bearings and trough for adjustment about a horizontal axis in the plane of said work table, said saw frame comprising a cross bar adapted to coact with said bearings and trough and a pair of perpendicular arms bifurcated to form guides for 115 a saw, and means to secure said saw frame in 120 its adjusted position.

In testimony whereof we have hereunto 125 affixed our signatures.

EDWARD A. HOOVER.
